CLAIM

The ornamental design for a speaker device, as shown and described.

DESCRIPTION

FIG. 1 is a top perspective view of a speaker device showing our new design;

FIG. 2 is a bottom perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines in FIGS. 1-6 and 8 illustrate the portions of the design that form no part of the claimed design.

1 Claim, 6 Drawing Sheets

Related U.S. Application Data

continuation-in-part of application No. 29/615,769, filed on Aug. 31, 2017, now abandoned, and a continuation-in-part of application No. 29/615,773, filed on Aug. 31, 2017, now abandoned.
